Application February 3, 1950, Serial No. 142,222

29 Claims. (Cl. 57-487)

1

This invention relates to improvements in ring spinning frames and more particularly to improvements directed towards more economical operation.

There have been numerous spinning devices suggested in which end breaks are detected for each individual strand of fibers being spun and in which the respective roving is interrupted following any such break so as to prevent feeding roving from the creel and thus largely to avoid making scavenger waste and to avoid other disadvantages. The roving interruption is for the spindle on which the break has occurred and does not stop the spinning on spindles on which the strands being spun are still intact.

Such devices have proven either too complicated or cumbersome in their operation or not too reliable or not sufficiently economical to meet with public acceptance. In some cases they have made regular servicing of the frame during spinning too difficult for practical purposes.

The present invention aims to overcome these disadvantages of the prior art and to provide positive advantages. In this way the invention makes possible the actual saving of waste and of labour which theoretically could be obtained from detecting and interrupting mechanisms of the general type described above.

The invention is preferably embodied in a spinning frame having the following combination of features. The frame includes a plurality of spindles on each of which a strand of fibers is spun. There is a set of drawing rolls on each side of the frame through which the strands are fed to the spindles, a creel, and a plurality of roving bobbins in the creel from which the roving is fed to the drawing rolls. Collecting means is provided for scavenger waste. There is means for driving the drawing rolls and common driving means for a plurality of spindles. Four spindles, two on each side of the frame are generally driven by a tape-belt from a drum driving several belts. The plurality of drums necessary for driving all the spindles of the frame are driven from common driving means.

There is separate detecting means for each spindle responsive to the end which it is spinning. Separate interrupting means for each spindle is responsive to its respective detecting means so as to stop the roving being fed to that particular spindle at a position prior to the entry of the roving into the drawing rolls. This serves to prevent feeding the roving from the creel to that particular spindle thereby to reduce the making of scavenger waste by that spindle without inter-

2

fering with spinning of unbroken ends on other spindles.

Preferably, the detecting means is adapted to detect broken ends at a position between the drawing rolls and the spindle. Preferably, there is a trumpet just prior to the point of entry of the roving into the drawing rolls and each interrupting means includes an element adapted to engage the roving at a point adjacent to the trumpet.

According to a preferred form of the invention, each detecting means includes a sensing element capable of being reacted upon by the strand of fibers being spun and control means to actuate the interrupting means only actuatable by the sensing element when there is no reaction from the fibers. In one preferred construction, each detecting means includes a sensing element which makes intermittent movements into the path of the strand of fibers being spun. If the strand is intact, the sensing element continues to make its intermittent detecting movements but, if the strand is broken, that element permits actuation of its interrupting mechanism independently of the other detecting means. Preferably, several if not all the elements are caused to move from a common source of motion, but the individual motion of each element can be stopped without stopping that of the elements of the other detecting means.

In a preferred construction each detecting means includes a pivoted support and means for pivoting this support in reciprocating movements. The sensing element is pivoted to the support and has an extending portion for engagement with the strand of fibers being spun and a balancing portion extending in an opposite direction from the pivotal point. The balancing portion of the sensing element is adapted to over-balance the extending portion so that the balancing portion tends to take a predetermined path in the absence of pressure on the extending portion. There is control means having a control member projecting within said predetermined path.

45 This control member may be connected to a switch or to a fluid valve depending upon whether or not electricity or fluid pressure is used as the means for conveying the detecting impulse to the interrupting mechanism. The reciprocating movements of the support are adapted to cause movement of the sensing element into the normal path of the strand of fibers being spun. In this construction, the extending portion is deflected when the strand is intact so that the 50 balancing portion clears the said member. When

the strand is not intact the said member is contacted by the balancing portion. The connection between the control member and the interrupting means for that spindle actuates the interrupting means. Preferably, there is a signal which is connected to the said member also actuatable by this detecting means so that in addition to the interrupting of the roving, the broken end is signalled to the spinner. The signal may be visual, as for example an electric light, or audible, as for example a buzzer.

The combination may also include means for lessening doublings resulting from primary end breaks. This device is a means for controlling flying broken spinning ends and conveying them to the underclearer roll. This means may take the form of an apparatus for playing streams of air on the spinning ends in the direction of the underclearer roll so that when ends break any loose strands will be blown on to the surface of the underclearer roll.

Various other modifications and additions to the specific preferred structures will be evident from the detailed description to follow.

By interrupting the roving before it enters the drawing rolls, accumulation of waste on the underclearer rolls is practically eliminated. Further, the automatic interruption of the roving obviates a present primary job requirement of the spinner constantly patrolling his frames to prevent undue accumulation of waste from end breaks on underclearer rolls, which, in due course, would result in the displacement of broken ends from underclearer rolls, and, in degree, secondary end breaks.

Thus, by use of the expedients described, it is possible to eliminate the necessity of the spinner regularly patrolling his frames in order to take care of trouble which may or may not have developed. With this necessity eliminated, the invention contemplates the re-arrangement of the spinning labour load so that the time of the spinner may be fully utilized in productive work. This result will be developed by a further division of the labour load and a further specialization in the use of labour.

The present concept is of a group job in tending spinning frames rather than an individual job. According to the present invention, it will basically be arranged for one attendant to take care of end breaks with the number of spindles tended large enough so that he will be able normally to proceed from end break to end break with a minimum loss of travelling time. Creeling would also be the primary responsibility of a separate attendant and the cleaning functions usually performed by the spinner would be taken care of by learners or helpers. One attendant, probably the one responsible for creeling, would be in charge of the group and give general direction to its work.

This arrangement of group labour would also allow for greater efficiency in labour utilization as it would have sufficient flexibility to offset in a large degree the variations that occur in actual spinning loads that have to be carried by spinning labour. Because of the inherent nature of the material being processed and because of the variations that occur from period to period both in the previous processes and in the processing conditions, the incidence of end breaks at the spinning frames varies from hour to hour and from day to day. Further, as suggested above, on the basis of the manner in which creeling is started, the labour load to meet creeling require- 75

ments will vary from time to time. The immediate labour requirements for creeling would of course be readily visible while the labour requirements as regards end breaks at any one time would be evident from the system of signal lights explained in a later section. The group job proposed would make it possible to take care of these variations more advantageously than is possible when a single spinner is employed, and an increase in machine efficiency would thus be obtained.

This advantage can be developed because the cleaning functions, to be taken care of by learners, can be delayed for intermediate periods and the available time of the learners applied to creeling or piecing of end breaks, when, because of an increased incidence, these functions require more attention for short periods than can be given them by the regular attendants assigned to those jobs. Conversely when the creeling or end break labour loads are less than normal, the respective attendants can aid in the cleaning and bring it up to schedule. Thus a more balanced and economical labour situation can be developed under the group system.

This more balanced labour situation will also make a more satisfactory approach to job time studies of spinning possible and allow for better labour incentive pay plans which in the end result in greater economy of operation.

The desirability of attaining the objectives of this invention has been evident in operational spinning work for many years as the art of spinning is among the oldest of the modern arts of machine production. Costs in textile industries have also been developed in great detail so that the resulting economics could readily be estimated. The other factor required to allow the working out of the objectives was the satisfactory solution of the operational and control problems involved and some of these problems will now be discussed.

A review of the construction and operation of a spinning frame immediately indicates certain of the inherent problems that have to be solved to obtain the objectives outlined. First and foremost of the problems is that of the delicacy of the control that must be used and which at the same time must be reliable in action. The strand of cotton being spun, and with which we have to work, has little strength until the twist is put in it, and this does not occur until it is passing from the lower drawing rolls. Further the action of the control must not interfere with the technical spinning of the yarn. As opposed to this requirement, the control must be sufficiently rugged and so constructed that it will stand continual handling by attendants during the normal operation of the frames and not be put out of commission. It must also be so arranged as not to interfere in any degree with the normal operation of the frame even in the limited space available where operational procedures regularly occur. A further problem in the development of a practical method is the number of controls that are required, as a combination of detector and interrupter must be applied to each production unit of the frame, the spinning spindle, and the number of spindles per plant is ordinarily counted in the thousands. Thus obviously the means must be of a simplified design in order that its application can be made on an economic basis. In this connection, the substantial increase in the costs of labour and raw cotton in recent years are important

factors as the actual savings in labour and materials to be made have become much more important when translated into dollar values.

The practical problems are therefore ones of delicacy and reliability yet ruggedness, compactness, simplicity and low cost of manufacture and installation. In the means presented in this application, it is believed that all these problems have been solved so that the general objectives of this invention can be achieved on an economic basis.

It may also be of help in appreciating the invention to consider the general nature of automatic controls throughout the textiles industry and also the distinctions that exist between its different divisions. Actually, throughout the industry, automatic end break detectors, usually associated with machine stop motions which stop the entire machine, have been applied to many processes. The applications are, of course, particularly adapted to the specialized conditions that they have to meet. To indicate the general nature of such applications a brief review will now be given of typical controls in the different divisions of the manufacturing process.

In general, cotton mill processes may be divided into four categories which the industry considers as separate and distinct from one another, even though the cotton itself is processed progressively through each department.

The four groups of processes are as follows:

(1) Preparation of the cotton fiber for spinning.

(2) Spinning the cotton fiber into yarn.

(3) Preparation of the single yarn for use in the final end product. (Some single yarn is used in weaving cloth just as it comes from the spinning frame.)

(4) Weaving of cotton cloth.

Before expanding briefly on the general processing functions of the divisions of the manufacturing procedure, it may be pointed out, as would be expected, that because of the nature of the material being processed and formed, that textile equipment used in successive divisions of the manufacturing processes is often associated in design with that used previously.

Actually, in the main, the equipment is designed to process strands of fibers in both loose and film association and the basic procedures for controlling such strands, in general, remains the same. Basic distinctions made in the industry are based on the functions performed in the different divisions of the industry and not on the character of the equipment used.

The first of the general divisions of the cotton industry listed above, that of preparing the cotton for spinning, takes the raw cotton fibers as they come to the mill and progressively cleans, arranges the fibers and draws them out in the form of roving that is suitable for use on the spinning frame. A typical automatic control in this group of processes would be that applied to the drawing frames where, if one end of card sliver breaks, the drawing frame is stopped so it may be pieced up. Otherwise, the drawing sliver would not be of the correct weight.

The second or spinning division of the industry is always considered separately as it is at this process that the cotton fibers are formed into the yarns that are required. The techniques applied in this process allow for the formation of the many different yarns required to make the products for which they are to be used. The processes following spinning must take the single

yarn that has been produced and work with it to produce the finished end product. It is to this distinct and separate division of the cotton mill processes that this present invention is applied.

The third group of procedures listed above covering the further preparation of the single yarn for final use includes such processes as spooling, warping, twisting, winding and slashing. Some of these procedures are closely associated but they all have to do with the functions of processing the finished yarn to get it in the form or put-up desired for the final end product. A typical automatic control in this group would be that applied to the beam warper where if one thread, sometimes out of several hundred, breaks, the warper stops to allow it to be repaired.

In weaving automatic controls are applied to the warp threads so that the loom will stop if one breaks. Also, according to the type of loom and the use to which it is being put, controls which govern its operation are applied to weft yarns in various degrees.

The invention will now be described in more detail by reference to the accompanying drawings illustrating the preferred embodiment of it, and in which:

Detailed description

Referring more particularly to the drawings, the general arrangement of the spinning frame and mechanism, according to the invention, is as follows, sufficient of the conventional spinning frame parts being described to make clear the combination. On the roll stand A are mounted the drafting rolls B extending the length of the frame which draw roving from the bobbins C mounted in the spinning frame creel. Each roving R is drawn through a trumpet 40 and through the successive pairs of drawing rolls B, then through the thread guide 41 to the traveller 42 riding on the ring 43, and thence to the spindle bobbin D. An underclearer roll 45 on the roll stand A collects cotton fly and broken ends from the lower front drawing roll.

The roving R as it passes through the drawing rolls B is attenuated because each successive pair of drawing rolls B is geared to rotate faster than the previous pair. The twist is put into the strand of fibers by the relative rotating motions of the spindle and traveller as the yarn is drawn down from the drawing rolls through the thread guide 41 and traveller and wound on the bobbin. The spindle 48 and bobbin D are rotated by the tape 47 from a drive (not shown), while the traveller 42 is rotated on the ring 43 by the pull of the yarn. There are a number of spindles arranged side by side on the spinning frame each associated with the mechanism described for spinning a strand of fibers into yarn. The drawing rolls on both sides of the frame are driven through from a common source of power through gear trains at the end of the frame. The spindles are usually driven in fours, two on each side of the frame, by a tape-belt, the tapes being driven off a series of metal pulleys or drums mounted on a shaft running lengthwise through the base of the frame.

The drive for the above mechanism is conventional and well known in the art. It is made up as follows. The main drive is taken from a belt 10 which is driven from a source of power (not shown). The belt 10 drives a pulley 11 which in turn drives a drum 12 which runs from one end of the spinning frame to the other. The pulley 11 also drives a shaft 13 inside the drum and concentric to it. The shaft 13 and the drum 12 at the other side of the frame are connected with gearing as follows.

A gear 14 is mounted on the end of the shaft 13. The gear 14 meshes with a gear 15 on a stub shaft 16 which also carries a gear 17. The gear 17 meshes with a gear 18 mounted on a stub shaft 18b. The gear 18 drives a further gear 19. The gear 19 is carried on a shaft 20 which drives the front roll B'. On the shaft 20 is mounted a gear 21 which meshes with a gear 22. The gear 22 carries a smaller gear 23 which meshes with a gear 24. The gear 24 drives the shaft 25 of the back roll B3. On the shaft 25 is a gear 26 which drives an intermediate gear 27 which in turn drives a gear 28 mounted on the shaft 29 of the middle roll B2.

Similar gears appear on the other side of the frame to drive similar parts of the apparatus. The gear 18, for example, meshes with the gear 18a driving the latter. The gear 18a meshes with a gear 19a of a shaft 20a which drives the front roll. Likewise there are parts 21a, 22a, 23a, 24a, 25a, 26a, 27a, 28a and 29a which correspond

with parts already illustrated on the other side of the frame.

The drum 12 also drives a number of tapes 47. Each tape 47 drives four spindles. The tape is tensioned by a tensioning device 38. At each side of the frame there is a ring rail 31. The rail 31 is raised and lowered in synchrony with the other parts by well known mechanism which it is not thought necessary to show. The mechanism so far described in detail is conventional as will be recognized by those skilled in the art.

Applicant's apparatus and general arrangement

The spinning frame is equipped with control mechanism for each spindle which detects a break in the end being spun and in response to this detection interrupts the roving in advance of the drawing rolls. This control mechanism includes in combination with the other parts of the frame, detecting means and interrupting means, actuating means for each of these means and an operative connection between them. The detecting means shown is indicated generally by E and its actuating means by F. The interrupting means is indicated generally by G. The detecting means is capable of determining when an end of yarn being spun has been broken; or when the yarn is being spun from a double roving, to determine when one end of roving has been broken. The actuating mechanism F is to supply the motive force for operating the mechanism E. The interrupting means G responds to the detection of a broken end, as described, and interrupts the roving being fed before it enters the first pair of drawing rolls B.

Detector mechanism

Referring more particularly to Figure 2 is a particular preferred form of detecting mechanism will be described in detail although it is not intended to limit the invention in its broader aspects to any particular detecting mechanism. This mechanism includes a base 52 which is mounted on the lappets by clamps or bolts or on other suitable mounting 50 in essentially the same position, if necessary. The box 51 extends upwardly from the base 52, and is generally rectangular in shape, including walls for accommodation of parts to be described. In the front wall of the box 51 are a pair of spaced-apart openings 55 which form bearings for lugs 57 projecting from the end of the elevating plate 58 which is thus pivotally mounted within the box. The other end of the elevating plate is connected to a coil spring 60, the other end of which is connected to an extension 61 at the base of the box. Between the bottom 52 of the box and the elevating plate 58 is a bellows or bladder 62 which, through the utilization of air pressure has the function of raising the elevating plate against the weight of the mechanism and the action of the spring 60. The plate, on being raised, pivots around the openings 55 by means of the special mountings of the lugs 57.

On each side of the plate 58, are pedestals 65 which are flat members rising above the edge of the box 51 when the detector mechanism is in the "rest" position. Extending through openings in the top of the pedestals 65 is a wire member 66 of substantially the shape indicated in Figure 2 and has a portion 68 adapted to contact the strands of fibers being spun at a position between the drawing rolls and the thread guide. The wire member 66 is so balanced that its rear

portion outweighs the front portion. So, as the motion of the detector develops, the rear portion will ride along the top of the box 51 unless the wire 66 is otherwise actuated.

An elevating plate stop bracket 75 extends upwards and inwards from the rear of the back wall of the box 51 and is adapted to contact the end of the elevating plate 58 in the extreme "testing" position, as indicated, for example, in Figure 6.

On one side of the box is mounted the control mechanism, which will now be described (see Figure 2). This mechanism includes a control lever member 78 pivoted to the side of the box as at 79 and having an upwardly extending arm with a detent end 80 designed to allow the rear edge of the wire 66 to catch it as the wire is moved forward when the strand of fibers is broken, by the raising of the plate 58. The lever 78 also has a rearwardly extending arm 82 and a forwardly extending arm 83.

When the arm 78 is moved forward by the wire 66 the cam 85 on the end of the arm 83 pushes closed a spring contact 87 which closes the circuit of a solenoid attached to the interrupting mechanism and which in turn causes the interrupting mechanism to act. The cam in its forward movement first closes the contact 87, then moves past it to allow this contact to open, thus de-energizing the solenoid and the interrupter. The cam 85 is so hinged that on resetting the control mechanism to the "rest" position it will pass the spring contact 87 without closing it.

As the lever 78 is moved forward, the arm 82 is moved upwards. This action allows the latch lever 90, which is hinged to the side of the box and urged inward by a spring as at 91 (Figure 12), to swing its lower end 93 inward through an opening 94 in the side of the box and to engage the upper edge of the plate 58 when it returns to its "rest" position. The end of the latch lever 90 thus holds the plate 58 in the "rest" position, until the lever 78 is reset manually against the spring, which action returns the latch lever 90 to the "free" position, shown in Figure 11.

The lever 78 at its extreme forward position also closes a spring contact 95 which lights a signal light 96. The lever 78 is held on its pivot against the side of the box by a spring washer or is set in a tight bearing so that it will remain in any position in which it is set or moved to, until a further actuating force is applied to it.

It is thus seen that when an end breaks the interrupting mechanism is actuated and the signal light 96 is also lighted.

There is also a further position of the lever 78 which is designed to allow the spindle to remain "dead" if for instance it is mechanically out of order. This is the position where the lever is pushed rearwardly just enough to open the light contact but not sufficient to remove the latch lever 90 from its latching position on the plate 58, as shown in Figure 12.

Actuating mechanism

The actuating device F (Figure 1) for the detecting mechanism includes a source of air pressure which may be drawn from the compressed air supply of the plant. The air is introduced through a hand valve into a supply tube 100 passing through an automatic valve 101 which is actuated by a plunger 103. The upper end of the plunger is in contact with an eccentric cam 105 which is timed to supply pulsations as required. The plunger is held against the cam

by the spring 106. The air under pressure is admitted by the valve 101 and passes through an orifice 107 into a chamber or receiver 110. From the receiver a supply pipe extends the length of the frame and from it flexible tubing 62a is used to convey the air pressure to the bladders or bellows 62 which actuate the detector mechanisms which are applied to each spinning strand of yarn. There is a larger orifice 111 in the receiver 110 which serves as a bleeder valve. The flow of air coming into the receiver 110 through the orifice 107 is, however, sufficient so that pressure will build up in the receiver 110 despite the air bled through the orifice 111 until the pressure is sufficient to open the safety valve 112. When the valve 101 is closed, the air pressure in the system is vented through the orifice 111. This allows the bellows or bladders to deflate and the detector mechanisms E to return to the "rest" position. One receiver 110 is common to a plurality of the expansible members operating the detecting mechanisms for the respective spindles, preferably common to all the expansible members on both sides of the frame.

Interrupter mechanism

The interrupter mechanism G (see Figure 3) includes a base plate 120 having side flanges 122. These flanges are provided with slots 123 adapted to act as guideways for purposes to be described. With arms 125 projecting one into each slot of the flanges 122 is the cutter or interrupter bar 130. This bar is formed with, or has mounted on it, a serrated edge 131 and a rearwardly projecting shelf or apron 133. A riser 142 is mounted in a bearing made by the bracket 143 which forms an extension of the base plate 120. The riser is connected to and urged by a spring 144 towards the upper position. The riser is attached to the interrupter bar 130. The riser is normally held in the downward position by a projecting detent 147 which engages the arm 149 of the solenoid 150. The solenoid 150 is connected by electrical wiring 152 to the contact 87. This contact is closed by the detecting mechanism E when an end is broken. This action energizes the solenoid and releases the riser 142 for upward movement thus causing the cutter bar 131 to cross the path of the roving and interrupt it.

Use of apron

The function of the apron 133 at the back of the serrated edge 131 is to hold the broken ends of the roving in a position essentially at the trumpet so that it is readily accessible to the spinner as he comes to fix the end break. The apron has a surface to which the fibers of the roving will adhere thus retaining them in that position.

An alternative to actuating the interrupter by electrical means, is to start it through pneumatic means with a suitable automatic valve arrangement and an air connection from the detecting mechanism and a release to allow the riser 142 to operate. In one such arrangement the arm 78 actuates an automatic spring air valve which allows air under pressure to reach the interrupter through flexible tubing. An expansible chamber, or bladder, on the interrupter replaces the solenoid 150 and operates to release the catch 149 in the event of an end break. Such a device is shown in Figure 4a. The catch 149 is connected through a rod 160 with a piston head 161 operating in a cylinder 162. The cylinder is sealed at the opposite end by screw plug 163. The piston

head 161 is normally urged into closed position by a spring 164. An air inlet 165 to the cylinder is connected with a supply line 166 which leads to a supply of air controlled by the detecting mechanism. When an end breaks air is supplied through the line 166 and the inlet 165 causing the piston 161 to move to the right. This allows the catch 149 to clear and release the detent 147. This is a known arrangement and does not "per se" constitute a part of the invention. If pneumatic actuating means is used for the interrupter, a mechanical signal such as a small flag can be substituted for the signal light.

Detecting mechanism operation

The operation of the detecting mechanism is as follows. Let us suppose that all yarns are pieced up and the spinning frame is running normally. The timing motion actuating the cam 105 and through it the automatic valve 101 allows the air to be introduced into the actuating system F which in turn supplies air pressure to the detecting mechanism E. This causes the bellows 62 to be inflated and the elevating plate 58 to rise. As the elevating plate 58 rises in its rotary motion around the pivots 57 the portion 68 of the detector wire is brought in contact with the strand of fibers R'. If the strand is intact the end of the detector wire is carried downward toward the thread guide as shown in Figure 6. This action raises the rear of the detector wire so that it passes over the top of the lever 78 without contact. When the air supply is shut off the pressure in the actuating system F is released through the orifice 111 thus allowing the detecting mechanism to return to the "rest" position. These motions are repeated on each air pulsation set up by the timing mechanism, as long as the strand of fibers remains intact.

If the strand of fibers has been broken, however, then there is nothing to deflect the portion 68 of the detector wire 66 and its rear portion slides forward along the top of the box, as the motions are developed, and hooks the detent end 80 of the lever 78 thus moving it forward and operating the various contacts and controls as previously described. The motions so far described are those which occur when spinning from a single roving.

Detecting mechanism operation when spinning from a double roving

It is also common practice to take roving from two bobbins in the creel and spin them into a single end of yarn. Occasionally, in this type of spinning the roving supplied from one bobbin breaks in the creel. This may result in the continual spinning of a strand of yarn from roving being drawn from only one bobbin. The application of the mechanism to this problem will now be described.

The principle involved in the detection of a strand of yarn being spun from a singling roving is not in itself new. As dealt with in this invention the detecting wire is forced against the strand of fibers being spun sufficiently to strain the strand so that it will break it, if it is only being spun from a single roving but not hard enough to break it, if it is still being spun from a double roving. This action is illustrated in Figure 9. When the motion is started the detector wire 66 first contacts the strand of fibers then tilts downward so that the rear of the detector wire rides over the end of the lever 78. As the motion progresses the rear of the detector

wire is carried up against the extension of the elevating plate stop 15, and then as the detector wire rides along this stop it pulls the front of the detector wire upward and against the strand of fibers. At this point, the strain put on the strand of fibers will break it if it is being spun from a singling roving but will not if it is still spun from a double roving.

If the strand of fibers does break then on the next testing cycle the interrupter will be actuated and the roving supply cut off. The electrical circuits operating the respective interrupting and signal units are preferably fed from a common source of power.

An optional element of the combination for lessening doublings is as follows. This is a means associated with the detecting mechanism for controlling loose flying broken spinning ends and conveying them to the underclearer roll. This objective is accomplished by having vents or nozzles from which air is blown in front and above the drawing rolls, so that loose flying strands of fiber as they come through the rolls will be caught in and carried by air currents to the surface of the underclearer roll. For example, this may take the form of a tube 73 (Figure 1) running lengthwise of the frame with vents in it from which air is expelled in a direction that will carry loose flying ends to the underclearer rolls. Alternatively, the same result may be obtained by having a series of tubes carried over the drawing rolls from the rear, with outlets so placed as to develop the desired air currents over the strands of fibers coming through the drawing rolls. Such tubes may be flexibly mounted and readily removable so that cleaning and other servicing functions will be interfered with to a minimum extent. There is preferably a vent or vents to control possible loose flying ends for each spindle.

Alternative form of detecting mechanism

Figure 16 illustrates an alternative form of detecting mechanism. A bell crank is fulcrumed as at 158 and includes one arm 170 having a head 172 adapted to contact the strand of fibers being spun. The other arm 175 extends rearwardly and runs in a cam control mechanism as will be described. The crank also includes a bracket 176 on which an adjustable counter-weight 178 is mounted. The whole assembly is so counter-weighted that it will tend to fall forward carrying the head 172 against the strand of fibers being spun.

The cam mechanism is mounted on a bar 183 which is arranged to move transversely of the spinning frame. During the transverse motion the arm 175 rides along the cam track 180 to a position 184. At this position the head is retained from falling forward by the strand of fibers if it is still intact and the arm 175 merely rides back to its initial position 179. If the strand of fibers is broken the head is allowed to fall forward and the arm 175 rides upwards in the portion 185 of the cam track to a position 186. As the cam is carried back the arm 175 goes through the slot portion of the track 181, contacts the pivotally mounted lever 189, the end of which rises and closes the contact 190 which operates the interrupter mechanism. The lever arm 175 continues down the cam track to the position 192 and back to its rest position as at 179. The latch 193 allows the passage of the cam in a downward direction but bars its entry into the passage 192 in the upward direction. The latch 193 is urged to the closed position by a spring 194.

In Figures 19 and 20 is illustrated a cam arrangement for use in testing when spinning from a double roving. In this device there is a lower track 200 along which the arm 175 normally rides from the starting position to the point 201. It then starts upwards from the point 201 riding back through the channel 203 and then to the downward channel 204. In so doing it forces the head 172 outward to a position where if spinning is being done from a singling roving it will break the strand. Then, on the next reciprocation of the cam, the arm 175 will ride along the channel 205 to contact the lever arm 207 which, on raising, closes the contact 208, which actuates the interrupter mechanism. The lever arm 175 then passes downward through this channel 204 to its rest position.

Alternative interrupter mechanism

Figure 21 shows an alternative form of interrupting mechanism. In this mechanism, the solenoid 210 when actuated from the detecting mechanism pushes the riser 211 upwards. The top of the riser, which is a wire, has a hooked end 212 running over the top of the rod 213 which end comes in contact with the end of the interrupter wire 215 causing it to rotate clockwise (looking at Figure 21) to a point where gravity becomes effective and causes the horizontal portion 216 to fall across the front of the trumpet 40, interrupting the roving.

In Figure 24, when the solenoid 220 is actuated by the detecting mechanism, the core 221 rises, pulling up the lever 222 whose catch 223 releases the cutter bar 224. The cutter bar is thus free to rotate upwards by action of the spring 225 across the mouth of the trumpet 40 thus severing the roving.

Figure 26 shows another form of detector mechanism. The underclearer roll 45 is mounted on the levers 231 pivotally mounted to the roll stands as at 233. The lever 231 is counter-weighted by the weight 235 so as to urge the underclearer roll 45 upwards against the lower front drawing roll B. According to the invention, the underclearer roll, which ordinarily is rotated by running in contact with the lower front drawing roll is further actuated through the series of rolls 243 and 244 and also held by these rolls in a forward position in its mounting grooves in the levers 231.

When an end breaks, the underclearer roll accumulates the roving from the broken ends which build up in a ball on the underclearer roll thus forcing the underclearer roll away from the roll B. At the same time, it forces the lever 249 in a rearward direction, the lever being pivoted as at 241.

As the lever arm 249 is moved back, the rearwardly extending arm 250 connected to the arm 249 is given an downward motion. The end of the lever 250 has a pivoted contact arm 252 which extends transversely to the lever. The end of the arm 250 normally rests against the stop 255 as the bracket 262 to which the two arms 249 and 250 are attached is counter-weighted by the adjustable counter-weights 261 so that it will tend to fall forward. The rest position is adjusted to bring the head of the lever 249 adjacent to the underclearer roll.

When the lever 249 is moved in a rearward direction the end 250 moves down from the stop 255 and brings the contact nob 256 to the contact base 258. This action actuates a signal to the operator that attention is needed. As the

ball of lint on the underclearer roll continues to build up, if the end is not pieced-up the lever 249 is moved further in a rearward direction and in the resulting motions eventually the contact nob 260 reaches the contact base 263 and this action actuates the interrupter mechanism.

Alternative mechanism

The detecting mechanism shown in Figure 29 is in many respects similar to that shown in Figure 2. So, for the parts of Figure 29 which correspond substantially to those of Figure 2, similar numbers have been used but raised into the 300's. The main operating detector wire 366 is provided with a catch wire 301 which is provided with a portion 368 adapted to contact the strand of fibers being spun. The wire 301 is hung and rotates freely on the wire 366 as indicated. As the mechanism starts to operate and the wire 365 is moved forward, the movement brings the portion of the catch wire 368 into contact with the strand of fibers R' and the catch wire is thus rotated carrying its rear portion 302 inwards and upwards. The trip wire 305 is also pivotally mounted on the cross bar 310 and extends forward and backward having a forward portion 311 and a rearwardly extending portion 312 which is sufficiently heavy to overbalance the front portion. As the motion of the detector develops a lateral extension of the rear portion 312 rides along the top of the box raising the front portion 311 until it comes into contact with the back edge 302 of the catch wire which has been rotated inward as explained above. The laterally extending portion of the back of the catch wire is then carried upward by the forward portion of the trip wire 311 until its arms contact the wire 366 where it is stopped. Thus the rear part of the trip wire 312 is caused to clear the catch lever 378. The wire 366 is controlled in its motion by its hinging to the cross bar 310 mounted on the pedestal 365 and the lateral loop 313 of one arm which rides between the top 315 of the box 351 and a wire on the side of the box. As soon as the trip wire 311 is held by the extension of the catch wire 302 coming in contact with the main detecting wire 366 then the whole wire mechanism is governed to ride downward out of contact with the strand of fibers by the contour of the cam 315. These motions continue as long as the strand of fibers R' is intact.

When the strand of fibers R' is broken the catch wire 301 has no outside turning force applied to it, so it does not engage the trip wire 311 as it rises toward the detector wire 366. The rear extension of the trip wire 312 is thus allowed to engage the hook 380 on the lever 378. This action develops control motions similar to those described in connection with Figure 2.

For example, the lever 378 has a rearwardly-extending arm 382 and a forwardly-extending arm 383. The lever 378 is pivoted to the side of the box as at 379. The end of the lever 382 is pivotally connected as at 384 to a piston rod 385. The piston rod 385 is connected to a piston head 386 which operates in a cylinder 387. A supply line 388 supplies air to the lower end of the cylinder and another line 389 connects the lower end of the cylinder with the interrupting unit, for example, through a supply line 166 as shown in Figure 4a.

Normally the piston head 386 blocks the bottom part of the cylinder 387 and prevents air passing through the supply line 388 to the interrupter line 389. But, when the lever 378 is

pulled forward the plunger 386 is lifted allowing air to pass from the line 388 to the line 389. A latch lever 390 arranged in the same manner as the lever 90 in Figure 1 serves the same function. The valve arrangement involving the plunger 386 is of a known or customary type and is not "per se" a part of the invention but merely a convenient type of element for the combination claimed.

Figure 32 illustrates this tripping motion. The same results can be developed by having the catch wire catch the trip wire when the controls are to be actuated and allowing it free motion when the strand of fibers is intact.

In cases where it is wished to check spinning from a double roving the cam 315 is designed to pull the main operating detector wire 366 up into contact with the strand R' to a predetermined point, after the primary strand detecting motion has been completed.

Another possible variation in the detecting motions of the detector shown in Figure 29 is one in which the catch wire 301 is normally held against the main operating detector wire 366 by the front end of the trip wire 305 while in the rest position. At the start of the detecting motion the rear of the trip wire 305 rides in a groove which acts as a cam surface and is carried upward so that the catch wire is released by the downward motion of the forward end of the trip wire. The catch wire then tends to rotate but if the strand of fibers is intact it is held in a position so that its rear edge will intercept the path of the forward end of the trip wire. If, however, the strand of fibers is broken the catch wire will rotate far enough so that its rear edge will clear the path of the end of the trip wire. The further relative motions are then similar to those outlined previously.

When it is not necessary to test for spinning from a double roving the construction of the detector can be modified so that the main operating detecting wire 366 can be held in firm association with the box frame and the trip wire 305 really becomes a portion of the elevating plate.

Alternative form interrupting mechanism

Figure 33 illustrates an alternative form of interrupting mechanism. This mechanism is mounted on the bar 400 having transversing action, which normally carries the trumpets just in rear of the back drawing rolls B. The mechanism includes a tube and trumpet combination 440 which guides the roving to the drawing rolls. Just behind the drawing rolls is a solenoid-operated riser 402 which is actuated by the solenoid 403 energized from the detecting mechanism. The end of the riser 402 is equipped with a head 404 for interrupting the roving. The head 404 is raised into the tube 440 through an opening in the bottom of the tube 420 by the riser. The brackets 412 are pivotally connected to the frame of the mechanism and there is mounted thereon a roll 415 and another roll 416 having friction contact therewith.

In the top of the tube there is an opening 410 through which the roving may be contacted by the roll 415. The bracket 412 is normally held in position with the rolls out of contact with the roving as shown in Figure 33 by a spring 418. When the roving is broken and it is desired to feed it into the drawing rolls it is merely necessary to push the rolls downward into position where the lower roll is in contact with the roving and to rotate the upper roll in counter-clockwise

direction thus rotating the roll 415 in clockwise direction and causing the roving in the tube to be pushed forward toward the drawing rolls. There is a catch 417 which is adapted to hold the riser in the upper position in the tube to stop any tendency of the roving to fall out after it has been interrupted by trapping it against the top of the tube. The riser is released by a lever mechanism actuated when the roll 416 is pushed forward.

Figure 35 shows an arrangement very similar to that of Figure 34 and like numbers have been given except that they have been raised by 100. Instead of the roller 415 the bracket includes a lever 515 pivotally mounted as at 517. The top of the lever bracket includes a finger rest 505 and downward and forward pressure on this finger rest causes the foot of the lever 515 to enter the slot 510 in the tube, and to push the roving forward so as to feed it to the drawing rolls. The same catch arrangement as in Figure 34 is used to hold the riser in upper position and it is released in the same manner by a lever connection when the automatic feed is actuated.

It is understood that the expedients specifically illustrated are merely preferred forms embodying the inventive concept and that the scope of the invention should not be limited to them. The sub-titles used are merely to facilitate reference and should otherwise be disregarded.

We claim:

1. A spinning frame, comprising; a plurality of spindles on each of which yarn is spun; a set of drawing rolls from which the strand is fed to the spindles; a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each of said detecting means including a pivoted support, means for pivoting said support in reciprocating movements, a sensing element pivoted to said support and having an extending portion for engagement with the strand of fibers being spun and a balancing portion extending in an opposite direction from the pivotal point, the balancing portion of the sensing element being adapted to over-balance the extending portion whereby the balancing portion tends to take a predetermined path in the absence of pressure on said extending portion, a switch element having a switch member projecting within said predetermined path, the reciprocating movements of the support being adapted to cause movement of the sensing element into the normal path of the strand of fibers being spun whereby said extending portion is deflected when the strand is intact thereby causing the balancing portion to clear said switch member, said switch member being connected to the interrupting means for that spindle.

2. A spinning frame according to claim 1, in which there is a switch actuatable by the movement of said switch element, said switch being connected to a signal.

3. A spinning frame according to claim 1, including a catch actuatable by the movement of said switch element to retain said support stationary when the switch element is in closed position.

4. A spinning frame according to claim 1, in

which the support is mounted on a base, a fluid pressure expandable member between the support and the base, a receiving chamber common to a plurality of said expandable members, a connection between said receiving chamber and said expandable members, a bleeding orifice in said chamber, an admitting orifice in said chamber, a safety valve attached to said chamber, said chamber being connected with an automatic admission valve which allows the fluid to be admitted to the pressure system as required.

5. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, said detecting means including a switch, separate interrupting means for each spindle for stopping the roving being fed to that spindle at a position prior to the entry of the roving into the drawing rolls, said interrupting means including an interrupter head adapted to cross the path of the roving and to sever it prior to its entry between the drawing rolls, a support connected to said interrupter head, means normally urging said support in a direction to cause the interrupter head to move across the path of the roving, a catch mechanism normally retaining said support in rest position and means actuated by said detecting means for releasing the catch mechanism said means including a solenoid in circuit with the switch on said detecting means.

6. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each of said detecting means including a movable member adapted to move in a testing cycle, means for moving said member, a sensing member reacted upon by the strand, control means, the sensing member movable by said movable member and being adapted to allow the movement of said movable member to cause operation of said control means when the strand is not intact, said sensing member adapted to be held by the strand when intact so that said movable member does not cause actuation of the control means, each interrupting means being responsive to its respective control means, whereby when an end is not intact the roving is severed prior to reaching the drawing rolls.

7. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate in-

interrupting means for each spindle for stopping the roving being fed to that spindle at a position prior to the entry of the roving into the drawing rolls, each of said detecting means including a pivoted support, means for pivoting said support in reciprocating movements, a sensing element pivoted to said support and having an extending portion for engagement with the strand of fibers being spun and a balancing portion extending in an opposite direction from the pivotal point, the balancing portion of the sensing element being adapted to over-balance the extending portion whereby the balancing portion tends to take a predetermined path in the absence of pressure on said extending portion, a control element having a control member projecting within said predetermined path, the reciprocating movements of the support being adapted to cause movement of the sensing element into the normal path of the strand of fibers being spun whereby said extending portion is deflected when the strand is intact thereby causing the balancing portion to clear said control member, said control member being connected to the interrupting means for that spindle.

8. A spinning frame according to claim 7, including a catch actuatable by the movement of said control element to retain said support stationary when the control element is in closed position.

9. A spinning frame according to claim 7, in which the support is mounted on a base, a fluid pressure expandable member between the plate and the base, a receiving chamber common to a plurality of said expandable members, a connection between said receiving chamber and said expandable members, a bleeding orifice in said chamber, an admitting orifice in said chamber, a safety valve attached to said chamber, said chamber being connected with an automatic admission valve which allows the fluid to be admitted to the pressure system.

10. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each interrupting means being responsive to its respective detecting means whereby when an end is not intact the roving is severed prior to reaching the drawing rolls thereby to prevent feeding of the roving from the creel without stopping the spinning of unbroken ends on other spindles thereby to reduce the collection of waste in said collecting means, and means associated with each interrupting means for feeding the forward end of the roving between the drawing rolls including means for supporting the roving, and a movable element positioned adjacent to the roving and adapted to be moved downwardly and forwardly in contact with the roving.

11. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing

rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each interrupting means being responsive to its respective detecting means whereby when an end is not intact the roving is severed prior to reaching the drawing rolls thereby to prevent feeding of the roving from the creel without stopping the spinning of unbroken ends on other spindles thereby to reduce the collection of waste in said collecting means, and means independent of the drawing rolls for causing flying broken ends to migrate to said underclearer roll.

12. A spinning frame according to claim 11, wherein the means for causing flying broken ends to migrate to said underclearer roll includes means for creating a jet of air.

13. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, the detecting means including a sensing member adapted to sense the strand of fibers being spun at a position between the drawing rolls and the spindle, separate interrupting means for each spindle for severing the roving being fed to that spindle at a position prior to the entry of the roving into the drawing rolls, each interrupting means being responsive to its respective detecting means whereby when an end is not intact the roving is severed prior to reaching the drawing rolls thereby to prevent feeding of the roving from the creel without stopping the spinning of unbroken ends on other spindles thereby to reduce the collection of waste in said collecting means, means for urging the sensing member into the path of the strand, a movable member whose movement causes the action of the interrupting means, and means active depending upon the position of said sensing member for moving said movable member.

14. A spinning frame, comprising a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, a guide tube adapted to guide and support a substantial length of roving located just prior to the point of entry of the roving into the drawing rolls, separate interrupting means for each spindle for stopping the roving being fed to that spindle at a position prior to the entry of the roving into the drawing rolls, each interrupting means including an element adapted to engage the roving at a point within the tube whereby the roving is severed within said tube and the broken end remains supported within said tube, each interrupting means being responsive to its respective detecting means whereby when an end is not intact the roving is severed prior to reaching the drawing rolls thereby to prevent feeding of the roving from the creel without stopping the spinning of unbroken ends

on other spindles thereby to reduce the collection of waste in said collecting means.

15. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, said detecting means including a control member, a movable sensing member, actuating means for moving one of said members into contact with the other, said sensing member being urged independently of said actuating means into the path of the strand of fibers being spun, said sensing member being adapted to be engaged and retained by the strand when intact but to be moved past the normal path of the strand when the latter is not intact.

16. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each detecting means including a sensing member mounted for movement from a first neutral position to a second strand sensing position to a third strand broken position, means for moving said sensing member from said first to said second and third position, said means including a movable member, actuating means for actuating said movable member whereby it moves the sensing member at least from first to second position, and means acting on said sensing member to cause its movement from second to third position when the strand is broken.

17. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each detecting means including a support member, for movement between a neutral position and a strand access position, a sensing member supported by the support member for movement between a strand sensing position and a strand broken position, actuating means for moving said supporting member, control means, one of said members being adapted to cause the other member to actuate said control means when the sensing member is in strand broken position.

18. A spinning frame, comprising, a plurality

of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, the detecting means including a movable member mounted to move in a testing movement, a sensing member for sensing the strand being spun movable by the movable member, a switch mechanism, the action of the interrupting means actuatable by said switch mechanism, means normally causing the sensing member to cause actuation of said switch mechanism, the sensing member being held by the strand of fibers being spun when intact from actuating said actuating member; as it moves from said second to said third position.

25. 19. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, the detecting means including a movable member, a sensing member pivotally mounted on said movable member and weighted whereby one end engages said strand and the other end is elevated adapted to sense whether the strand of fibers being spun is intact or broken, switch means actuatable by engagement with the sensing member, the movable member adapted to act on the sensing member to move it into contact with the switch means only when the strand is broken, each interrupting means being responsive to the switch means of its respective detecting means whereby when an end is not intact the roving is severed prior to reaching the drawing rolls.

20. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each of said detecting means including a movable member adapted to move in a testing cycle, means for moving said member, a sensing member pivotally mounted on said movable member and adapted to be reacted upon by the strand, said sensing member having a sensing part adapted to engage the strand and a balancing part adapted to over-balance the member when the strand is broken, switch means, the sensing member being arranged to allow the

movement of said balancing part into engagement with said switch means when the strand is not intact, said sensing member adapted to be held by the strand when intact so that said movable member does not come into engagement with the switch means, each interrupting means being responsive to its respective switch means whereby when an end is not intact the roving is severed prior to reaching the drawing rolls.

21. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each detecting means including a control member, a movable sensing member, actuating means for moving one of said members into contact with the other, said sensing member being movable from a first neutral position to a second strand sensing position to a third strand broken position, means urging said sensing member independently of said actuating means from said second position to said third position, the strand normally reacting on said sensing member to retain it in said second position against the tendency of said means urging it towards said third position, actuating means responsive to the position of one of said members adapted to be actuated through the movement of the sensing member from second to third position.

22. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for severing the roving being fed to that spindle at a position prior to the entry of the roving into the drawing rolls, each detecting means including a control member and a sensing member located adjacent thereto, said sensing member being adapted to contact the strand between the drawing rolls and the thread guide, actuating means for moving one of said members into contact with the other, other means normally urging a contacting part of said sensing member into the path of the strand of fibers, said contacting part of the sensing member being adapted to be engaged and retained by said strand when intact but when the strand is not intact to move past the normal path of the strand, each interrupting means being responsive to its respective detecting means whereby when an end is not intact the roving is severed prior to reaching the drawing rolls thereby to prevent feeding of the roving from the creel without stopping the spinning of unbroken ends on other spindles thereby to reduce the collection of waste in said collecting means.

23. A device according to claim 22 wherein the movable member is a piston operating in a cylinder, the cylinder has an air outlet port normally closed by the piston, and the piston is moved by

the sensing member when the strand is broken to uncover the port, the interrupting means being air operated and having a communication with said port.

24. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, the detecting means including a movable sensing member adapted to sense whether the strand of fibers being spun is intact or broken, control means actuatable by the movement of the sensing member, and movable means adapted to act on the sensing member to move it into contact with the control means when the strand is broken, the sensing member being pivoted on said movable means and having a sensing part and a balancing part, the balancing part being adapted to urge the sensing part into the path to move the control means when the strand is broken, the control means including a switch arm movable by engagement with the sensing member, each interrupting means having instrumentalities responsive to the control means of its respective detecting means whereby when an end is not intact the roving is severed prior to reaching the drawing rolls thereby to prevent feeding of the roving from the creel without stopping the spinning of unbroken ends on other spindles thereby to reduce the collection of waste in said collecting means.

25. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each of the detecting means including an element adapted to contact the strand of fibers being spun, a cam mechanism for each element, each cam mechanism including a cam track, each element including a cam engaging member engaging in said track, control means on each cam mechanism in said track whereby it can be engaged by said cam engaging element, common means for operating the cams for a plurality of the elements, the detecting element being arranged so that cam elements engage control means only when the strand of fibers being spun is not intact.

26. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle respon-

sive to ends which are not intact, separate interrupting means for each spindle for stopping the roving being fed to that spindle at a position prior to the entry of the roving into the drawing rolls, each of the detecting means including an element adapted to contact the strand of fibers being spun, a cam mechanism for each element, each cam mechanism including a cam track, each element including a cam engaging member engaging in said track, control means on each cam mechanism in said track whereby it can be engaged by said cam engaging element, common means for operating the cams for a plurality of the elements, the detecting element being arranged so that cam elements engage control means only when the strand of fibers being spun is not intact, each of said cam means being a reciprocating cam having a cam track in which said control means is located.

27. A spinning frame comprising, a plurality of spindles on each of which yarn is spun, a set of drawing rolls from which the strand is fed to the spindles, means for supplying roving to the rolls for each spindle, means for driving the drawing rolls and spindles, a thread guide between the drawing rolls and spindles, separate detecting means for each spindle responsive to an end break, separate interrupting means for each spindle for severing the roving being fed to that spindle at a position prior to the entry of the roving into the drawing rolls, the detecting means including a sensing member adapted to contact the strand between the drawing rolls and the thread guide, each interrupting means being responsive to its respective detecting means whereby when an end is not intact the roving is severed prior to reaching the drawing rolls thereby to prevent feeding of the roving from the creel without stopping the spinning of unbroken ends on other spindles thereby to reduce the collection of waste in said collecting means.

28. A device of the type described comprising detecting means including a pivoted sensing member, a fluid pressure operated member for acting on said sensing member to move it into the path of the strand, said detecting member adapted to be held in non-interrupting position by said strand and allowed to move into interrupting position when the strand is broken, air operated interrupting means responsive to said detecting means on the breaking of a strand to interrupt the strand adjacent to a supply point.

29. A spinning frame, comprising, a plurality of spindles on each of which yarn is spun, a set of drawing rolls from which the strand is fed to the spindles, a creel and a plurality of roving bobbins on the creel from which the roving is fed to the drawing rolls and collecting means for scavenger waste, means for driving the drawing rolls and common driving means for a plurality of spindles, separate detecting means for each spindle responsive to ends which are not intact, separate interrupting means for each spindle for stopping the roving being fed to that spindle at a position prior to the entry of the roving into the drawing rolls, each detecting means having a sensing member adapted to contact the strand of fibers being spun between the drawing rolls and its respective spindle, each control means including a moveable member, each detecting means having a sensing member balanced so that it normally tends to allow the interrupting movement of the moveable member, the sensing member being adapted to be overbalanced by the strand of fibers being spun when intact so that it does not allow the interrupting movement of the moveable member, but being adapted when the strand being spun is not intact to move to allow said moveable member to make an interrupting movement, each interrupting means being responsive to its respective control means.

ERLE F. SAUNDERS.
